ADJUSTABLE BAFFLE ARRANGEMENT FOR
USE WITH STEAM GENERATING BOILERS

Reinier P. De Vries, Melrose, Mass.

Application December 5, 1947, Serial No. 789,995

6 Claims. (Cl. 110—98)

1

This invention relates to improvements in steam generating boilers of the water tube type.

Steam generating boilers of the water tube type, as heretofore constructed, are usually provided, in association with a bank of water tubes thereof, with an arrangement of baffles or partitions so designed and placed as to direct the movement of hot gases of combustion, from the firebox of the boiler, through the water tube bank whereby to cause said gases to flow in contact with the water tube surfaces substantially throughout the lengths of the tubes before discharging through the boiler stack. The provision of such baffles or partitions is neither satisfactory or efficient, not only because they are costly to install and replace, but, in use, tend to trap and collect fly ash, so that masses of such ash pile up on portions of the baffles or partitions and accumulate around and cover portions of the water tubes, with the consequence that both free flow of the hot gases to the boiler stack is impeded, and contact of said hot gases with the covered portions of the tubes is blocked, with resultant loss of tube heating surface and drop in tube efficiency.

Having in mind the above cited and other objections to the use of gas flow directing baffles or partitions in association with a bank of tubes in a water tube type boiler, it is an object of this invention to provide a novel construction and arrangement of adjustable means which is located above and entirely separate from the bank of tubes in a water tube type boiler, and which is adapted, when properly adjusted, to so influence the draft induced flow of hot gases of combustion from the boiler fire box upwardly through the bank of tubes, and ultimately to the boiler stack, that substantially uniform contact of the hot gases with the entire surface area of the tubes throughout the lengths thereof is assured with substantially uniform heat transfer to said tubes. The invention having for a further object to provide a gas flow directing and controlling means of the character mentioned which avoids draft obstruction of spaces intermediate the water tubes by accumulations of fly ash therein; and which avoids accumulation of fly ash in covering relation to tube surfaces with heat transfer limiting effect.

Other objects of this invention, not at this time more particularly enumerated, will be understood from the following detailed description of the same.

An illustrative embodiment of this invention is shown in the accompanying drawings, in which:

2

Fig. 1 is a fragmentary longitudinal vertical sectional view of a steam generating boiler of the water tube type which is equipped with the novel means for directing and controlling draft induced flow of hot gases of combustion from the boiler fire box through the bank of boiler water tubes in accordance with the purposes and principles of this invention; Fig. 2 is a transverse vertical sectional view of the same, taken on line 2—2 in Fig. 1; and Fig. 3 is a fragmentary horizontal sectional view of the same, taken on line 3—3 in Fig. 2.

Fig. 4 is a fragmentary detail longitudinal sectional view, somewhat enlarged, taken through a portion of the gas flow directing and controlling means; and Fig. 5 is a fragmentary transverse vertical sectional view of the same, taken on line 5—5 in Fig. 4.

Similar characters of reference are employed in the above described views, to indicate corresponding parts.

Referring to the drawings, the reference characters 10 and 11 respectively indicate the front and back walls of the housing of a steam generating boiler, the side walls of which are indicated by the reference character 12. Suitably supported at the top of the boiler housing are one or more steam collecting drums or domes 13, preferably disposed to bridge the front and back walls of said housing. Leading outwardly from the upper interior of the boiler housing, as e. g. through the front wall 10 as shown, adjacently beneath the steam collecting drums or domes 13, is a smoke pipe or other suitable conduit 14 which extends to the boiler stack or chimney (not shown). Within and across said smoke pipe or conduit 14 is pivotally mounted a draft control damper 15, which may be and usually is automatically actuated in suitable manner, as already well known to the art.

Located within and across the upper interior of the boiler housing, beneath the steam collecting drums or domes 13, is a bank 16 of spaced water tubes, the tubes of which incline upwardly through the housing interior from front to back thereof. The tubes of the bank 16 thereof are connected by their lower ends to and in communication with a forward manifold 17, the latter being, in turn, connected by piping 18 with the forward end portions of the steam collecting drums or domes 13; and, similarly, said tubes are connected by their upper ends to and in communication with a rearward manifold 19 which, in turn, is connected by piping 20 with the rearward end portions of the steam collecting drums

or domes 13. The water tubes of the bank 16 may be cleaned through the blow down line 21 which is connected to and in communication with the lower end of the forward manifold 17. Any well known means (not shown) may be used to supply boiler feed water. The above described arrangement and setting of the bank of water tubes is one most commonly used, but, as will be understood, may be varied, if desired, to suit other designs of boilers of the water tube type, so long as the setting and arrangement admits of installation of the hereinafter described novel means for directing and controlling draft induced flow of hot gases of combustion from the boiler fire box upwardly through the spaces intermediate the tubes.

The means for directing and controlling draft induced flow of hot gases from the boiler fire box upwardly through the spaces intermediate the water tubes of the bank 16 is disposed within the upper interior of the boiler housing above said bank 16 of water tubes and beneath the steam collecting drums or domes 13, and comprises a ceiling member or plate 25 of a width to extend across the housing interior from one to the other of the side walls thereof, and from the back wall forwardly to a point adjacent to the front wall 10. Said ceiling member or plate 25 is preferably positioned to incline somewhat downwardly from said back wall 11 toward the front wall 10 of the boiler housing. The ceiling member or plate 25, as thus disposed, subdivides the upper interior of the boiler housing so as to form a water tube bank containing chamber 26 below the same, and a gas collecting chamber 27 above the same and beneath the steam collecting drums or domes 13. Said gas collecting chamber 27, thus provided above the ceiling member or plate 25, communicates directly with the intake end of the smoke-pipe or conduit 14 through which the gases of combustion are discharged to a boiler stack or chimney by the draft effect of the latter. If required, an auxiliary ceiling partition 28 is provided to extend between the forward end of the ceiling member or plate 25 and the front wall 10 of the boiler housing, at a point of the latter below the level of the intake of said smoke-pipe or conduit 14, thus assuring the sealing off of the outlet end of the gas collecting chamber 27 from the water tube bank containing chamber 26, whereby to prevent flow of gases from the latter to the smoke-pipe or conduit 14 in by-passing relation to the gas collecting chamber 27.

The ceiling member or plate 25 can be supported in its above described operative position within the boiler housing interior in any convenient manner; preferably, however, the same is suspended by hanger bolts 29 which depend from bracket members 30, the latter being suitably secured, as e. g. by welding, to drums or domes 13. Any suitable number and disposition of such hanger bolts 29 may be employed, accordingly as a given size and weight of the ceiling member or plate 25 may be deemed to require.

The ceiling member or plate 25 is preferably made of cast iron, and may comprise a single or one-piece body, or it may be formed by a plurality of joined sections which are suitably secured together. In any case, the ceiling member or plate 25 is provided with a plurality of longitudinally extending, laterally spaced apart slots or ports 31, which extend from front to back of the boiler housing interior, and in direction corresponding to the direction of exten-

sion of the water tubes contained in the bank 16 thereof. The ceiling member or plate 25 is preferably reenforced against warping by upstanding longitudinally and laterally extending ribs 32 and 33 which are integral therewith, certain of which bound the margins of said slots or flues 31 (see Fig. 3).

Movably supported upon the ceiling member or plate 25 are a plurality of cover or damper plates 34 which respectively cooperate with the respective slots or ports 31 of said ceiling member or plate, and which can be slidably shifted relative to said slots or ports 31 so as to form operative open areas of the latter which taper from the rearward ends toward the forward ends thereof, whereby to offer variable resistance to gas flow through the slots or ports along the lengths thereof and into the gas chamber 27. By thus shaping the effective open areas of the slots or ports 31, maximum resistance to gas flow therethrough occurs at the ends of the slots or ports nearest to the point of draft induced discharge of gases through the smoke pipe or conduit 14, where the draft suction is of maximum effect, which resistance gradually diminishes along the slots or ports toward the ends of the latter which are at greatest distance from said point of draft induced discharge of the gases through the smoke-pipe or conduit 14, and where the draft suction is of minimum effect. In this manner upward flow of the hot gases of combustion, rising from the boiler fire box, as induced by draft suction through the gas collecting chamber 27, is substantially equalized from front to back of the bank 16 of water tubes, and consequently contact of said gases and transfer of heat therefrom to the water tubes of the bank 16 is substantially uniformly applied to the water tubes throughout the lengths thereof, so that necessity for the use of gas flow directing baffles or partitions in association with said bank 16 of water tubes, and the objectionable consequences attendant upon the use of such baffles or partitions, hereinabove referred to, are avoided.

Means are provided for adjustably shifting and determining desired positions of said cover or damper plates 34 relative to the slots or ports 31, whereby to taper or shape the effective open areas of the latter. To this end, each cover or damper plate 34 is provided with an upstanding medial flange or web 35 which extends longitudinally therealong from the forward end portion to the rearward end portion thereof. These flanges or webs 35 not only stiffen and reenforce the cover or damper plates against warping and distortion, but also provide means for coupling manipulatable shifting and adjusting devices thereto. The shifting and adjusting devices are engaged with opposite end portions of said flanges or webs 35, and are common to corresponding end portions thereof. Said shifting and adjusting devices comprise a forward shift rod 36 which is provided with screw-threaded opposite end portions 37 and 38 respectively slidably extended through and so as to project exteriorly of opposite side walls 12 of the boiler housing, with the body of said shift rod extending transversely across the forward end portions of the cover or damper plates 34, and a rearward shift rod 39 also provided with screw-threaded opposite end portions 40 and 41 which are likewise respectively slidably extended through and exteriorly of opposite side walls 12 of the boiler housing, with the body portion of this shift rod extending trans-

versely across the rearward end portions of the cover or damper plates 34. Said shift rods 36 and 39 extend through slots 42 with which the end portions of the flanges or webs 35 of the cover or damper plates 34 are provided. Fixed on the shift rods 36 and 39, adjacent to opposite sides of the flanges or webs 35 of the cover or damper plates through which they pass, are collars 43 which, by abutment upon said flanges or web portions, function to translate axial movements of the shift rods into lateral shifting movements of the cover or damper plates 34. Screwed onto the respective screw-threaded opposite end portions 37 and 38 of the forward shift rod 36, which project exteriorly from the respective side walls 12 of the boiler housing, are the respective lock nut sets 44 and 45; and, similarly, screwed onto the respective screw-threaded opposite end portions 40 and 41 of the rearward shift rod 39, which likewise project exteriorly from the respective side walls 12 of the boiler housing, are the respective lock nut sets 46 and 47.

It will be understood that the fire-box of the boiler is located, as indicated by the reference character 58, in the lower interior portion of the boiler housing beneath the bank 16 of water tubes, so that the hot gases of combustion, generated in the fire-box by combustion of suitable fuel, will rise so as to pass through the spaces between the water tubes contained in the bank 16 thereof.

As is well known the upward flow of gases of combustion is induced by the draft uptake by which said gases are discharged through the boiler smoke-pipe and stack. Since the intake of the smoke-pipe is usually through a wall of the boiler housing, and since the suction effect of the draft is at its maximum in those portions of the boiler housing interior which are adjacent to said intake, the gases, as influenced by draft suction, tend to flow at highest velocity through the path of least resistance and most direct to the smoke-pipe intake. For this reason, unless otherwise prevented, the gases, although efficiently contacting those portions of the bank of water tubes which are nearest to the smoke-pipe intake, will tend to by-pass or make inefficient heat transfer contact with the portions of the bank of water tubes which are remote from the smoke-pipe intake. To avoid such unequal heat transfer contact of hot gases with the bank of water tubes it has, in the past, been customary to provide baffles and partitions so disposed, in association with and in relation to the bank of water tubes, that the gases are first compelled to contact remote portions of the water tubes and thereafter portions of the latter which are more closely adjacent to the smoke-pipe intake. The objections to the use of such baffles and partitions has been already above referred to.

By the present invention, the necessity for use of baffles or partitions within the bank of water tubes has been avoided by the provision of the ceiling member or plate 25 having the longitudinal slots or ports 31 and the adjustable cover or damper plates 34 cooperative with the latter, and as interposed between the draft influenced gas collecting chamber 27, through which draft induced suction is effected, and the water tube bank containing chamber 26 through which initial up flow of gases of combustion occurs.

In use, the cover or damper plates 34 are so adjusted relative to the slots or ports 31 as to narrow the latter at points nearest the smoke-pipe intake, and thence gradually widen the same toward the points most remote from said smoke-

pipe intake. In this way, restrictive resistance to up-flow of gases in the zone of maximum draft suction is set up, which resistance is gradually reduced toward the zone of minimum draft suction. As a consequence of this, the draft suction effects are substantially equalized throughout the cross-sectional area of that portion of the boiler housing interior which provides the water tube bank containing chamber 26, and consequently the up-flow of gases through the water tube bank is substantially uniform in volume and velocity from end to end of the latter.

The cover or damper plates 34 may be adjusted by manipulation of the shaft rods 36 and 39. For example, the lock nut sets 45 and 47 being loosened, by turning home the opposite lock nut sets 44 and 46 against the adjacent side wall 12, the shift rods may be drawn to the right (as viewed in Fig. 3) respectively for different distances or amounts, whereby to obliquely offset the cover or damper plates 34 relative to the slots or ports 31, in such manner that the desired tapered open areas of said slots or ports 31 are formed. The amount of relative adjustment of the opposite ends of the cover or damper plates, which may be required in any given case, can be determined by taking thermometer readings at opposite ends of a slot or port 31, and then manipulating the cover or damper plates until the compared readings are of substantially the same degree.

After the cover or damper plates 34 have been desirably adjusted, the same and the shift rods may be secured against accidental displacement by tightening the loosened lock nut sets 45 and 47. It will, of course, be obvious that the cover or damper plates 34 may optionally be adjusted either to the right or left.

Having now described my invention, I claim:

1. A steam generating boiler provided by a housing having a fire-box in its lower interior, a bank of water tubes within the fire-box, a ceiling member above the water tubes to provide a chamber in the upper interior of the housing, said ceiling member having ports in the form of elongated slots through which gases of combustion pass from the fire-box upwardly into said chamber, a draft inducing means communicating with an end of the chamber through a side wall of the housing whereby to discharge said gases from the chamber, said port forming slots extending lengthwise in direction substantially parallel to the direction of outward flow of gases from the chamber to and through the draft inducing means, damper plates cooperative with and extending longitudinally of the port forming slots, and means cooperative with opposite ends of the damper plates for laterally adjusting the same relative to the port forming slots, whereby to taper the latter toward the draft inducing means so as to set up maximum resistance to upward gas flow through the port forming slots at points subject to maximum suction effect of the draft inducing means with diminishing resistance toward points of decreasing suction effect of the draft inducing means.

2. A steam generating boiler as defined in claim 1 wherein the means for adjusting the damper plates comprises the provision, in connection with opposite end portions of each damper plate, of an upstanding flange having a slotted opening therethrough, shift rods common to the damper plates respectively extending across their corresponding end portions 75 through the slotted openings of the flanges

thereof, collars affixed on said shift rods in straddling relation to the flanges of each damper plate, opposite end portions of the shift rods respectively extending slidably through and exteriorly of opposite side walls of the housing, and manipulatable nut means threaded onto the exterior end portions of said shift rods, said shift rods being individually axially movable to laterally shift the damper plates relative to the port forming slots for passage tapering effect.

3. A steam generating boiler provided by a housing having a fire-box in its lower interior, a bank of water tubes within the fire-box, a ceiling member above the water tubes to provide a chamber in the upper interior of the housing, said ceiling member having parts in the form of elongated slots through which gases of combustion pass from the fire-box upwardly into said chamber, a draft inducing means communicating with an end of the chamber through a side wall of the housing whereby to discharge said gases from the chamber, said port forming slots extending lengthwise in direction substantially parallel to the direction of outward flow of gases from the chamber to and through the draft inducing means, laterally shiftable damper plates cooperative with and extending longitudinally of the port forming slots, means to pivot the end portions of said damper plates which are disposed adjacent to the discharge end of the chamber and the draft inducing means, and means cooperative with the opposite end portions of the damper plates for laterally adjusting said damper plates relative to the port forming slots, whereby to taper the latter toward the draft inducing means so as to set up maximum resistance to upward gas flow through the port forming slots at points subject to maximum suction effect of the draft inducing means with diminishing resistance toward points of decreasing suction effect of the draft inducing means.

4. A steam generating boiler as defined in claim 3 wherein the means for positioning the damper plates comprises the provision, in connection with opposite end portions of each damper plate, of an upstanding flange having a slotted opening therethrough, shift rods common to the damper plates respectively extending across their corresponding end portions through the slotted openings of the flanges thereof, collars affixed on said shift rods in straddling relation to the flanges of each damper plate, opposite end portions of the shift rods respectively slidably extending through and exteriorly of opposite side walls of the housing, and manipulatable nut means threaded onto the exterior end portions of said shift rods, the shift rod cooperative with the ends of the damper plate which lie adjacent to the discharge end of the chamber and the draft inducing means being manipulatable to determine pivoting points for said ends of the damper plates, and the other shift rod being axially movable to laterally shift opposite ends of the damper plates relative to the port forming slots for passage tapering effect.

5. A steam generating boiler provided by a

housing having a fire-box in its lower interior and a steam collecting means at its top, a bank of water tubes within the fire-box, a ceiling member extending across the interior of the housing above said bank of water tubes whereby to provide a chamber beneath said steam collecting means, said ceiling member having gas ports in the form of elongated slots through which gases of combustion from the fire-box, after traversing the bank of water tubes, pass upwardly into said chamber, a draft inducing means communicating with an end of the chamber through a side wall of the housing whereby to discharge gases from the chamber, said gas ports extending lengthwise in direction substantially parallel to in direction of outward flow of gases through the chamber to and through the draft inducing means, damper plates respectively longitudinally coextensive with said respective gas ports, and respective means cooperative with opposite end portions of the damper plates manipulatable to shift the latter to diagonally disposed relation to the gas ports so as to taper the effective gas passage areas of said ports toward the draft inducing means, whereby to set up maximum resistance to upward gas flow through the ports at points subject to maximum suction effect of the draft inducing means with diminishing resistance toward points of decreasing suction effect of said draft inducing means.

6. A steam generating boiler as defined in claim 5 wherein the means for positioning the damper plates comprises the provision, in connection with opposite end portions of each damper plate, of an upstanding flange having a slotted opening therethrough, shift rods common to the damper plates respectively extending across their corresponding end portions through the slotted openings of the flanges thereof, collars affixed on said shift rods in straddling relation to the flanges of each damper plate, opposite end portions of the shift rods respectively slidably extending through and exteriorly of opposite side walls of the housing, and manipulatable nut means threaded onto the exterior end portions of said shift rods, the shift rod cooperative with the ends of the damper plate which lie adjacent to the discharge end of the chamber and the draft inducing means being manipulatable to determine pivoting points for said ends of the damper plates, and the other shift rod being axially movable to laterally shift opposite ends of the damper plates relative to the gas ports for passage tapering effect.
